SWIMMING POOL

Donald E. Pruess, 5 Timber Trail, Rye, N.Y.

Filed Apr. 29, 1960, Ser. No. 60,369

Term of patent 14 years

(Cl. D13—1)

Des. 189,811

PAGE 2

FIG. 2

FIG.3

FIG.4

I claim:

The ornamental design for a swimming pool, as shown.
